(57) **CLAIM**

We claim the ornamental design for display screen with icon, as shown and described.

DESCRIPTION

The file of this patent contains at least one drawing executed in color. Copies of this patent with color drawings will be provided by the Office upon request and payment of the necessary fee.

FIG. 1 is a front view of a first embodiment of a display screen with icon;

FIG. 2 is a front view of a second embodiment of the display screen with icon; and,

FIG. 3 is a front view of a third embodiment of the display screen with icon.

The broken line showing of the display screen is for the purpose of illustrating environment and forms no part of the claimed design. The broken line showing of elements on the display screen illustrate portions of the article and form no part of the claimed design.

1 Claim, 2 Drawing Sheets
(2 of 2 Drawing Sheet(s) Filed in Color)

FIG. 1

FIG. 2

FIG. 3
